WILLIAM E. McDONELL, OF ROCHESTER, NEW YORK, ASSIGNOR TO E. KIRSTEIN SONS COMPANY, OF ROCHESTER, NEW YORK, A CORPORATION OF NEW YORK.

OPHTHALMIC MOUNTING.

1,264,410.

Specification of Letters Patent. Patented Apr. 30, 1918.

Application filed December 6, 1917. Serial No. 205,860.

To all whom it may concern:

Be it known that I, WILLIAM E. McDONELL, a citizen of the United States, and resident of Rochester, in the county of Monroe and State of New York, have invented certain new and useful Improvements in Ophthalmic Mountings, of which the following is a specification.

The present invention relates to ophthalmic mountings and more particularly to the type shown in the patent to William R. Uhlemann, #1,036,036, granted August 20, 1912, in which there is provided a support for holding the lenses in properly spaced relation, and carrying nose guards which engage the nose under the action of springs, the nose guards and the springs being held detachably on the support by pivoted latches or keepers. An object of this invention is to provide a construction in which the latches are mounted to turn about axes coincident with the turning axis of the guards, so that the pivot pins of the guard levers may also be utilized for supporting the latches. Another object of the invention is to provide latch-held guards in which the springs for positioning the guards also act on the latches to hold the latter in latching position. A still further object of the invention is to form the pivot pins which provide the connection between the guards and the supports with two separated bearing surfaces, one for a guard lever and the other for a latch, these surfaces being either upon the same side of the support or on opposite sides with one above and the other below such support.

To these and other ends the invention consists of certain parts and combinations of parts all of which will be hereinafter described, the novel features being pointed out in the appended claims.

In the drawings:

Figure 1 is an enlarged plan view of a portion of one embodiment of the ophthalmic mounting in plan;

Fig. 2 is a vertical section through the mounting shown in Fig. 1;

Fig. 3 is a view, partially in side elevation and partially in section, of the embodiment shown in Fig. 1;

Fig. 4 is a perspective view of the latch employed in Fig. 1;

Fig. 5 is a view similar to Fig. 1, showing another embodiment in which the latch is slightly modified;

Fig. 6 is a perspective view of the latch employed in Fig. 5;

Fig. 7 is a vertical transverse section through a mounting in which the latch is arranged on the under side of the support, while the guard is mounted on the upper side;

Fig. 8 is a transverse sectional view through the mounting in which the guard and the latch are mounted on the same side of the support, but a recess is provided in the upper surface of the support for housing the latch;

Fig. 9 is a sectional view in the plane of the lenses, showing a different form of guard lever;

Fig. 10 is a view, partially in elevation and partially in section transverse to the plane of the lenses, of the embodiment illustrated in Fig. 9;

Fig. 11 is a sectional view in the plane of the lenses, showing a latch which is mounted on the pivot pin below the guard lever and has a bendable portion lying above the pivot pin to prevent the removal of the guard lever;

Fig. 12 is a view of a construction similar to that shown in Figs. 9 and 10, in which the form of the guard lever and the pivot pin are slightly modified; and

Fig. 13 is a sectional view transversely of the lenses of an embodiment in which the guard lever is bendable into engagement with the latch.

Referring first to the embodiment shown in Figs. 1 to 4, A indicates lenses of which there are two, as usual, connected by a suitable support. This support, in this instance, comprises a bridging portion 1 and lens attaching devices 2 connected to the bridging portion by horizontal portions or tables 3. These tables are, in this instance, perforated, and have pivot pins passed therethrough. In this embodiment, these pivot pins have portions 4 passing through the perforations of the tables with their lower ends spun or upset as at 5. Above the support the pivot pins have two bearings 6 and 7, in this instance separated by an annular flange 8, the bearing 7 being larger than the

portion 4 of the pivot pin in order that a shoulder may be provided to engage the support.

On the bearing 6 which is uppermost the 5 guard is mounted to turn. In this instance the guard is in the form of a sheet metal lever extending transversely of the lenses and having a finger piece portion 9 in front of the lenses, while the nose bearing portion, not shown, is arranged on said lever in rear of the lenses. Preferably, the guard lever has an upwardly-extending tubular portion 10, surrounding the bearing portion 6 and having an annular rib 11 at its upper 15 end. About the tubular portion 10 a helical or other coil spring 12 is arranged, one end 18 of this spring engaging the support for the lenses, while the other end is preferably engaged by the latch which retains the guard 20 lever in co-operative relation with its bearing 6.

The latch, in this instance, turns on the bearing 7 beneath the flange 8, so as to be confined between said flange and the top of 25 the table 3. This latch has two arms, one extending forwardly at 14, while the other extends rearwardly at 15, the bearing 16 being provided between said arms. The rear arm 15, in this instance, extends upwardly 30 at 17 into the plane of the guard lever, and then extends horizontally at 18 to overhang the guard lever. From this overhanging portion a portion 19 is bent horizontally by a return bend 20 to provide a recess in which 35 the end 21 of the spring 12 is received, so that such spring tends to hold the overhanging portion 18 over the lever, and in this manner prevents the removal of the lever from its bearing 6. To prevent accidental 40 movement between the latch and the guard lever, the latch also has a portion 22 extended upwardly into the plane of the guard lever; and from this portion 22 a portion 23 is extended horizontally above the guard 45 lever. Upon the under side of the portion 23 a boss 24 is formed by depressing the upper portion of the portion 23, and this boss is received within a depressed portion 25 in the upper surface of the guard lever 50 in front of the pivot of the latter.

To remove the guard lever the spring 21 is disengaged with the latch, and the boss 24 is moved out of the notch 25, so that the latch can be turned relatively to the guard 55 lever in order to bring the overhanging portions of the latch from positions above the guard lever, after which the guard lever may be removed in the direction of its turning axis, this being due to the fact that the 60 pivot pin on which the guard lever turns is headless. With the removal of the guard lever the spring 12 is detached.

In the embodiment shown in Figs. 5 and 6, the parts are the same except that the latch 65 is locked to the guard lever by a different

form of securing means. The forward arm 14 has a portion 22 bent upwardly therefrom on that side opposite the side shown in Fig. 4, and the portion 23^a is extended above the guard lever and is bendable with the portion 22^a to the plane of the latch, as shown in Fig. 6, so that the latch may be turned relatively to the guard lever.

In the embodiment shown in Fig. 7, the table 3 of the support for the lenses has a screw threaded opening which is engaged by a screw threaded portion 4^b on the pivot pin, the pivot pin, in this instance, having a bearing portion 6^b above the support for the guard lever, and a bearing portion 7^b below the support for the latch. The bearing portion 7^b is larger in diameter than the screw portion 4^b and forms a shoulder for abutting the under side of the support 3, and the lower end of the pivot pin is enlarged 85 at 5^b to act as a support for the latch. The guard lever has substantially the same form as that shown in Fig. 1, but turns in direct engagement with the upper face of the support, being surrounded by a spring 12 which 90 engages at one end with the support and at the other end with the latch. The latch turns on the bearing portion 7^b beneath the support and has but one arm 15^b which is provided with an upward or vertical extension 17^b in rear of the support, said extension having a portion 18^b overhanging the guard lever to retain the latter on the support. The return portion 19 is also provided to form a recess in which the end 21 of the 95 spring is anchored. In this construction no means other than that of the spring is provided for holding the latch with its overhanging portion above the guard lever.

In the embodiment shown in Fig. 8, the pivot pin 4^c is passed through the support 3^c and has its lower end upset at 5^c on the under side of the support. The top surface of the support is provided with a depressed portion or recess 26 which opens at the rear 105 of the support 3^c and has the latch mounted therein and turning upon a bearing portion 7^c, which is separated from the bearing portion 6^c by a tapered annular shoulder 8^c. The guard lever has a tubular portion 10 turning on the bearing portion 6^c and also 110 on the tapered annular shoulder 8^c, so that it lies close to the latch. The latch has but one arm 15^c which is extended rearwardly and is provided with a portion 17^c extending 115 upwardly into the plane of the guard lever in rear of the pivot, the upwardly extending portion carrying the overhanging portion 18^c, and the return portion 19 forming a notch for the portion 21 of the coil 120 spring 12 which surrounds the tubular portion 10. The portion 21^c of the coil spring beyond the portion 21 is bent into engagement with the guard lever to hold the latch to the guard lever. According to this em- 125 130

bodiment, the latch is not visible in the front of the mounting, and while the bearing portions between the two levers are separated, the two levers are brought close together.

In the embodiment shown in Figs. 9 and 10, the pivot pin is formed as in the embodiment shown in Fig. 7, with the bearing portion 6^a above the support, a screw threaded portion 4^a engaging the support, and a bearing portion 7^a below the support. A head 5^a on the lower end of the pivot pin supports the latch, while the guard lever is supported on the bearing portion 6^a. The guard lever, instead of being provided with a tubular portion, has a portion extended vertically with reference thereto at 27, and then turned inwardly at 28 to provide a bearing, the guard lever itself having a bearing 29 below the bearing 28. The coil spring 12 is arranged between the two bearing portions and has one end engaging the support at 13, while the other end 21 engages in the notch formed by the return portion 19^a on the overhanging portion 18^a which is formed at the upper end of a portion 17^a extended upwardly from the arm 15^a of the latch. The latch also, in this instance, has a forwardly-extending arm 14^a which is provided with an upwardly-extending portion 22^a carrying a portion 23^a extended above the guard lever and acting to prevent relative movement between the latch and the guard lever in the same manner as the embodiment shown in Figs. 5 and 6.

In the embodiment shown in Fig. 11, the pivot pin is constructed in the same manner as in the embodiment shown in Fig. 2. The guard lever has a tubular portion 10, which is not provided with a surrounding bead or flange at its upper end. This embodiment differs from Fig. 2 in having the latch formed with a vertical portion 31 to one side of the lever, said vertical portion having at its upper end a horizontal portion 32, which overlies the upper end of the tubular portion 10 and the upper end of the pivot pin, so as to retain the guard lever on the pivot pin. The portion 32 may be bent, as shown in dotted lines, so as to permit the guard lever and the spring to be removed, the spring having one end engaging the support and the other end connected to the guard lever.

In the embodiment shown in Fig. 12, the pivot pin has a screw threaded portion 4^e engaging the support 3^e, and also has a bearing portion 6^e above the support and a bearing portion 7^e below the support. The bearing portion 7^e is larger than the screw-threaded portion 4^e so as to form a shoulder for engagement with the under side of the support, and on this bearing portion 7^e the latch, which is formed in the same manner as that shown in Fig. 10, is mounted to turn,

the lower end of the pivot pin being enlarged at 5^e to support the latch. Above the bearing portion 6^e the pivot pin is provided with an annular recess or groove 30 in which the spring 12 is received, one end of the spring engaging the support and the other end engaging the latch in the same manner as in the other embodiments. The spring in this instance should be removed before the lever is removed.

In the embodiment shown in Fig. 13, the pivot pin is formed in the same manner as that shown in Fig. 2. The guard lever is also formed in the same manner and the mounting of the spring is the same. The latch has its rear arm formed like the rear arm of the latch of Fig. 2, but the connection between the forward arm and the guard lever is different. The guard lever has an opening 33 in the portion thereof bent downwardly in front of the support 3, and in this opening a finger 34 on the forward end of the latch is projected. Disengagement between the finger 34 and the guard lever is effected by bending the guard lever to carry the opening 33 away from the projecting finger 34, as shown in dotted lines.

From the foregoing it will be seen that the pivot pin for the guard lever is also utilized for supporting a latch which holds the guard lever in place. The coaxial mounting of the latch and the guard lever also permits the guard spring to be utilized for holding the latch in latching position. The arrangement of the latch on the pivot pin makes the latch inconspicuous and also reduces the cost of manufacture of the mounting. Owing to the fact that the portion of the pivot pin on which the guard lever turns is, in most of the embodiments, headless at its free end, the guard lever and the spring may be simultaneously removed.

It will be noted that the pivot pin has two bearings and two shoulders. The two shoulders are arranged on opposite sides of one of the bearings and one of the shoulders abuts the support for the lenses. The latch operates on the bearing between one shoulder and the support to be confined between these parts while the guard lever turns on the other bearing.

What I claim as my invention and desire to secure by Letters Patent is:—

1. An ophthalmic mounting comprising a support for the lenses, a guard lever detachably and pivotally mounted thereon, and a latch for securing the guard lever in place mounted to move with the guard lever.
2. An ophthalmic mounting comprising a support for the lenses, a nose guard, a pivot pin rigidly supported by one of said parts and formed with a headless bearing turning in the other part to permit the guard to be removed in the direction of the axis of said pin, a spring mounted on the guard lever

- about the pivot pin, and a latch mounted to turn about an axis coincident with the turning axis of the guard lever and to lock the guard lever against removal from the support for the lenses.
3. An ophthalmic mounting comprising a support for the lenses, a nose guard pivotally mounted on the support, a latch for holding said guard on the support, and a spring for 5 positioning the guard, acting on the latch to hold it in locking position.
4. An ophthalmic mounting comprising a support for the lenses, a nose guard pivotally mounted thereon, a latch for holding 10 the nose guard on the support said latch being mounted to swing about the axis of turning of the guard lever, and to engage said lever to one side of the axis, and a coil spring having its axis coincident with the 15 axis of the guard lever and having one end engaging the support and the other end engaging the latch.
5. An ophthalmic mounting comprising a support for the lenses, a pivot pin rigidly 20 secured to the support and having two separated bearings thereon, a nose guard turning on one of said bearings, and a latch turning on the other bearing and adapted to hold the guard on the bearing of the latter.
6. An ophthalmic mounting comprising a support for the lenses, a guard lever detachably and pivotally mounted thereon, and a pivoted keeper mounted to swing with and also relatively to the guard lever about the 25 axis of turning of said lever.
7. An ophthalmic mounting comprising a support for the lenses, a guard, a pivot pin secured against turning in one of said parts and having a bearing in the other part, and 30 a latch for securing the pivot pin in the bearing, said latch being held by said pivot pin.
8. An ophthalmic mounting comprising a support for the lenses, a pivot pin rigidly 35 secured to said support and having two bearings thereon and a shoulder between the bearings, a guard lever mounted above the shoulder on one of the bearings, and a pivoted latch mounted below the shoulder on the other bearing and engaging the guard lever 40 to hold the latter on the bearing above the shoulder.
9. An ophthalmic mounting comprising a support, a pivot pin passing through the support and having two shoulders and two 45 bearings, the two shoulders being situated on opposite sides of one of the bearings and one of them engaging the support, a latch ar-
- ranged on the bearing between the two shoulders to be confined between the support and the other shoulder, and a nose guard ar- 50 ranged on the other bearing and held thereon by the latch.
10. An ophthalmic mounting comprising a support for the lenses, a guard lever detachably and pivotally mounted thereon, a 55 latch for securing the guard in place, pivotally mounted on the support to turn about the axis of turning of the guard.
11. An ophthalmic mounting comprising a support for the lenses, a guard detachably 60 and pivotally mounted thereon, a latch for securing the guard in place, pivotally mounted on the support to turn about the axis of turning of the guard, and means for causing the latch to swing with the guard.
12. An ophthalmic mounting comprising a support for the lenses, a guard detachably 65 and pivotally mounted thereon, a latch for securing the guard in place pivotally mounted on the support, to turn about the axis of 70 turning of the guard and having a forwardly and a rearwardly extending arm, one of which overhangs the guard to hold the latter to the support, and the other of which interlocks with the guard to cause the latch to turn 75 with the guard.
13. An ophthalmic mounting comprising a support for the lenses, a guard detachably 75 and pivotally mounted thereon, and a latch for securing the guard in place pivotally mounted on the support to turn about the axis of turning of the guard and having a forwardly 80 and a rearwardly-extending arm both of which overhang the guard to hold the latter to the support.
14. An ophthalmic mounting comprising a support for the lenses, a guard detachably 85 and pivotally mounted thereon, a latch for securing the guard in place pivotally mounted on the support to turn about the axis of turning of the guard and having a forwardly 90 and a rearwardly-extending arm, one of which connects with the guard to hold the latter to the support, and a spring for the 95 guard engaging the other arm.
15. An ophthalmic mounting comprising a support for the lenses, a guard detachably 100 and pivotally mounted thereon, and a latch for securing the guard in place pivotally mounted on the support to turn about the axis of turning of the guard, and having an arm 105 overhanging the guard to hold the latter to the support.

WILLIAM E. McDONELL.
